PRODUCTION OF UNSATURATED FATTY ACIDS

Martin Luther and Hans Klein, Mannheim, Germany, assignors to I. G. Farbenindustrie Aktiengesellschaft, Frankfort - on - the - Main, Germany, a corporation of Germany

No Drawing. Application May 29, 1929, Serial No. 367,116. In Germany June 4, 1928

5 Claims. (Cl. 260—119)

The present invention relates to the production of unsaturated fatty acids.

The oxidation of paraffin hydrocarbons, waxes and the like by means of gases containing oxygen, at an elevated temperature furnishes products which contain, inter alia, large amounts of dark colored acid compounds and conversion products thereof, both of which are insoluble in petroleum ether. For many purposes, such for example as soapmaking, it is essential that these admixtures should be eliminated from the oxidation products.

We have now found that valuable mixtures of unsaturated and saturated carboxylic acids can be obtained from the oxidation products by subjecting the crude oxidation product to distillation. For example, the crude oxidation product may be distilled, preferably under reduced pressure, the operation proceeding smoothly and the 20 unsaturated and saturated acids and the like distilling over and leaving only a comparatively small residue. The heat of distillation effects an extensive conversion of the hydroxy carboxylic acids into unsaturated fatty acids, so that the 25 distillate no longer contains any hydroxy carboxylic acids and is suitable for direct use for many purposes. If esters of the hydroxy carboxylic acids and of saturated fatty acids be present in the crude oxidation products a considerable portion of the esters of the latter and those 30 of the unsaturated acids corresponding to the aforesaid esters of hydroxy carboxylic acids is found in the distillate. If desirable the distillation may be repeated one or more times. The 35 losses of material during the distillation are very slight, and above all, there is no appreciable splitting off of carbon dioxide from the acids, in contrast to the results obtained in a distillation of pure hydroxy carboxylic acids after isolating 40 these acids from a crude oxidation product of the aforesaid nature. This is evident from the saponification values of the products before and after distillation. Particularly in this respect good results are obtained by applying a current 45 of carbon dioxide during the distillation whereby the splitting off of carbon dioxide from the acids is practically completely avoided. The iodine value is increased to approximately three times its former value.

50 The unsaturated fatty acids contained in the distillate may be utilized without separation of the saturated carboxylic acids present in the mixture, or may be separated from the latter, in the manner already known, prior to use. The 55 mixture of acids may also be hydrogenated, be-

fore or after removing unsaponifiable materials, if such be present, the unsaturated acids being thereby converted into the saturated state.

The operation may also be carried out with an acid product which has been freed from un- 60 oxidized initial materials, for example by sub- jecting the crude oxidation product to mechanical pressure or to sweating below the melting point of the acids present, or with the entire acid portion of the oxidation product, both 65 which materials will be referred to, for the sake of brevity, in the following as a pretreated ox- idation product. Particularly good yields of un- 70 saturated acids are obtained when the oxidation of the paraffin hydrocarbons, waxes and the like has been performed rather strongly, for example with the aid of catalysts, since also such pre- 75 treated product is not liable to give the bad re- sults obtainable with pure hydroxy carboxylic acids stated above.

As a rule the distillation is preferably carried out in the presence of a current of an inert gas- 80 eous agent, such as carbon dioxide or water vapor and the like.

The distillation is advantageously carried out 85 rather quickly and with an addition of steam. After the second distillation the distillates are practically free from hydroxy carboxylic acids, and consist almost exclusively of valuable un- 90 saturated fatty acids. For some purposes, such as the preparation of solid edible fats, they may be subsequently hydrogenated. If desired, a cata- 95 lyst may be employed in the distillation, for ex- ample red phosphorus, sulphuric acid or metal oxides, but usually the employment thereof may be dispensed with, very good results being obtainable without the use of a catalyst.

The following examples will further illustrate 95 the nature of the invention, but the invention is not restricted to these examples. The parts are by weight.

Example 1

500 parts of an oxidation product obtained from hard paraffin wax, with the acid value of 100 108, a saponification value of 205, and containing 27 per cent of acids insoluble in petroleum ether, are distilled in a vacuum of 8 millimeters (mer- 105 mercury gauge) at 110° to 280° C. 432 parts of dis- tillate are obtained which has an acid value of 153, a saponification value of 200, and a content of only 5 per cent of acids insoluble in petroleum ether.

400 parts of the distillate are re-distilled, under 110 3 millimeters pressure and in an atmosphere of

CO₂, whereupon 384 parts pass over at from 140° to 290° C. The distillate has an unaltered acid value of 153 and a saponification value of 200, and contains only 2 per cent of acids insoluble in petroleum ether. The same procedure for the production of unsaturated acids may be followed in the treatment of the oxidation products from Montan wax, beeswax, ozokerite and the like.

and about 290° C. and at a pressure up to atmospheric pressure a crude product containing a substantial proportion of long chain hydroxy carboxylic acids from the super-oxidation of difficultly volatile paraffin hydrocarbons and waxes, 80 while passing an inert gaseous agent through the reaction vessel, thereby converting said, long chain hydroxy-carboxylic acids into long chain unsaturated fatty acids.

3. The process for the production of unsaturated fatty acids, which comprises subjecting to 85

distillation, at a temperature between about 110° and about 290° C. and at a pressure below atmospheric pressure, a crude product containing a substantial proportion of long chain hydroxy carboxylic acids from the super-oxidation of difficultly volatile paraffin hydrocarbons and waxes, 90 which crude product has been freed from unoxidized initial materials thereby converting the said long chain hydroxy carboxylic acids into long chain unsaturated fatty acids. 95

4. The process for the production of unsaturated fatty acids, which comprises subjecting to 100 distillation, at a temperature between about 110° and about 280° C. and at a pressure of about 8 millimeters of mercury, a crude super-oxidation 100 product of hard paraffin wax, thereby converting the long chain hydroxy carboxylic acids contained in said super-oxidation product into long chain unsaturated fatty acids. 105

5. The process for the production of unsaturated fatty acids which comprises subjecting to 110 distillation, at a temperature between about 110° and about 260° C. and at a pressure of about 15 millimeters of mercury, a crude oxidation product from soft paraffin wax, while passing a current of steam through the distilling batch, thereby converting the long chain hydroxy carboxylic acids contained in said oxidation product into long chain unsaturated fatty acids. 115

MARTIN LUTHER.
HANS KLEIN.

10 *Example 2*

100 parts of a crude oxidation product obtained from an oxidation of soft paraffin wax of brown coal tar and possessing an acid value of 108 and a saponification value of 205 are distilled at 15 millimeters mercury gauge while passing through a current of steam and raising the temperature up to about 260° C. 90 parts of a practically anhydrous mixture of an acid product are obtained after fractional condensation, the product showing an acid value of 146 and a saponification value of 200. When carbon dioxide is employed in the place of steam about the same yield with the same acid value is obtained and the saponification value is that of the initial material. The process is similar when an oxidation product of liquid paraffin hydrocarbons or of Montan wax be employed.

What we claim is:

1. The process for the production of unsaturated fatty acids, which comprises subjecting to 30 distillation, at a temperature between about 110° and about 290° C. and at a pressure up to atmospheric pressure a crude product containing a substantial proportion of long chain hydroxy carboxylic acids from the super-oxidation of difficultly volatile paraffin hydrocarbons and waxes, thereby converting said long chain hydroxy-carboxylic acids into long chain unsaturated fatty acids. 35
2. The process for the production of unsaturated fatty acids, which comprises subjecting to 40 distillation, at a temperature between about 110°
